UNITED STATES PATENT OFFICE

92,180

DESIGN FOR A STOCKING

Paul F. Kroener, Hyde Park, Pa., assignor to
Textile Machine Works, Wyomissing, Pa., a cor-
poration of Pennsylvania

Application October 14, 1932, Serial No. 45,348

Term of patent 14 years

To all whom it may concern:

Be it known that I, PAUL F. KROENER, a citizen of the United States of America, residing at Hyde Park, in the county of Berks and State of Pennsylvania, have invented a new, original, and ornamental Design for a Stocking, of which the following is a specification, reference being had to the accompanying drawing, forming part thereof.

Fig. 1 is a side view of a stocking embodying

my ornamental clock design, the opposite side thereof being the same.

Fig. 2 is an enlarged fragmentary view of a part of the stocking shown in Fig. 1, and illustrates the design approximately to actual size.

I claim:

The ornamental design for a stocking as shown and described.

PAUL F. KROENER.
